SHIPPING CONTAINER

Victor Willoughby, Ridgewood, N. J., assignor to
American Car and Foundry Company, New
York, N. Y., a corporation of New Jersey

Application July 22, 1931, Serial No. 552,375

2 Claims. (Cl. 220—1.5)

This invention relates to shipping containers of a kind adapted for use with gondola or flat cars for the storage and transportation of fractional car lots of merchandise.

One object of the present invention is the provision of a strong and durable shipping container of the kind described.

Another object of this invention is the provision of a shipping container having a strong and durable base frame structure for supporting either a wooden or a metal floor.

Another object of this invention is the provision of a shipping container having a base comprising a skeleton frame including transverse incompressible floor beams and longitudinally arranged stringers for supporting a floor.

A further object of this invention is the provision of a new and improved corner construction for shipping containers.

This invention also contemplates the provision of a shipping container for the storage and transportation of fractional car lots of merchandise which is formed in the main of metal parts welded together to produce a substantially unitary construction.

Other objects and advantages of this invention will be apparent from the following description taken with the accompanying drawings in which:

Figure 1 is a front elevation of the container.
Fig. 2 is a rear elevation of the container.
Fig. 3 is a broken side elevation of the container.

Fig. 4 is a sectional view on the line 4—4, Fig. 3, the view also showing fragmentary portions of the floor and the nailing strips; this view also showing clearly the construction of the base frame of the container.

Fig. 5 is a top plan view of a portion of the container.

Fig. 6 is an enlarged detail view of that portion of the container shown at the lower left-hand corner of Fig. 4.

Fig. 7 is a sectional view on the line 7—7, Fig. 6.

Fig. 8 is a sectional view on the line 8—8, Fig. 3.

Fig. 9 is a sectional view on the line 9—9, Fig. 8.

Fig. 10 is a sectional view on the line 10—10, Fig. 8.

Fig. 11 is a sectional view on the line 11—11, Fig. 3.

Fig. 12 is a sectional view on the line 12—12, Fig. 1.

Fig. 13 is a sectional view on the line 13—13, Fig. 1.

Fig. 14 is a sectional view on the line 14—14, Fig. 1, but showing the door in open position.

Fig. 15 is a sectional view on the line 15—15, Fig. 4.

Fig. 16 is a sectional view on the line 16—16, Fig. 2, and

Fig. 17 is a sectional view on the line 17—17, Fig. 3.

Referring now more particularly to the drawings in which similar characters of reference designate similar parts in the several views, the container of the present invention comprises generally a base A, side walls B, a roof C and front and rear end walls D and E, respectively, front end wall D having a door F therein.

The base A of the container comprises a skeleton frame, substantially rectangular in shape, and formed of side and end sills 2 and 4, respectively, angles in the instance shown, the horizontal legs 6 of which project inwardly. Referring now to Fig. 6, it can be seen that the adjacent ends of the sills 2 and 4 are mitered as at 8 and are welded together as shown at 10. To further connect adjacent sills angle braces 12 are provided which extend diagonally across and rest upon the horizontal flanges of the sills and are welded to said sills, as shown at 14; the vertical flanges 15 of the braces 12 being removed adjacent the ends of the braces in order not to overlap the sills.

The vertical legs 17 of the sills 2 and 4 serve as attaching portions for the side and end walls, the latter lapping said legs and being externally and internally welded thereto as shown at 16, see Fig. 7. The sills 2 and 4 and the adjacent side and end walls are further connected by angle shaped corner posts P which lap the side edges of adjacent side and end walls and are welded to the latter as shown at 18. To stiffen the structure at the corners, post stiffeners 20 are provided which are of plate form and are arranged diagonally of the corner posts between the respective legs thereof and are welded to said legs 45 and to the side and end walls and also to the horizontal legs of the sills 2 and 4 as shown at 22, the post stiffeners having their lower ends slightly offset as at 23 in Fig. 7 whereby to rest upon the horizontal flanges of the sills 2 and 4. 50

The rectangular base frame just described is provided with transverse floor beams 26 formed of I-beams which extend between and are supported on and preferably welded to the horizontal flanges of the side sills. In addition to 55

the floor beams 26, which are rigid incompressible members, the base frame also includes longitudinally arranged stringers 28, wood beams in the instance shown, which are supported by the lower flanges of the transverse beams 26 and by the end sills and the adjacent transverse floor beams. Angle clips 30 secured to the transverse beams 26 and to the stringers 28 serve to retain the stringers in position. The horizontal flanges 10 of the side and end sills have secured thereto in any suitable manner, nailing strips 32 and at the rear end of the container the adjacent longitudinal stringers 28 are connected thereto by angle clips 34, while at the front end of the container 15 the nailing strips include a thickened portion 36 defining a threshold which is covered by a threshold plate 38 secured to the vertical flange of the end sill (see Fig. 12) and the side edges of said threshold plate 38 lap the adjacent longitudinal stringers 28 and are secured thereto and to the floor in any suitable manner.

Secured to the threshold 36 as shown in Fig. 12 is an angle 40, the horizontal leg 42 of which serves to support the floor at this area of the container; the floor of the container comprising the transversely arranged wood planks 44 which extend from side sill to side sill and rest upon the nailing strips 32, and the superposed wood planks 46 which are longitudinally arranged and extend 30 from end sill to end sill and rest upon and are secured to the before mentioned floor planks 44. Obviously, the transverse beams 26 and longitudinal stringers 28 serve to support the floor.

The side walls B and rear end wall E are each 35 formed of metal sheets 48 and 50, respectively, overlapped on a horizontal line 52 and internally and externally welded together as shown at 54, see Fig. 11. The side walls B are each provided with spaced pairs of reinforcing ribs 56, one pair 40 on each side of the vertical center through the walls. In the instance shown these ribs are U shaped in section and are welded to said side walls and converge upwardly from the base A with their upper ends flattened as at 58 and arranged 45 between the overlapped walls 60 of lifting ears 62 carrying loops 64 for engagement by suitable tackle whereby the container may be lifted and moved about. The rear end wall E of the container is also stiffened by ribs 66, three 50 in number in the present instance, with their lower ends adjacently arranged and welded to the vertical flange of the end sill; the center rib being substantially vertical and arranged at the vertical center line of the rear end wall while the outer ribs 66 diverge upwardly and have 55 their upper ends arranged adjacent the upper corners of the end wall, as shown clearly in Fig. 2. In addition to the ribs 56 the side walls B are stiffened by horizontal ribs 68, one arranged 60 across the vertical center of the side wall and extending between adjacent ribs 56 with its ends preferably welded to said ribs and to plate 48, while the other horizontal ribs 68 are arranged between the pairs of ribs 56 and are welded there- 65 to and to plate 50. The rear end wall is further stiffened by horizontal ribs 70 welded to plate 50.

The upper ends of the side walls and rear end wall lap the vertical flanges 72 of side and end plates 74 and are welded thereto as shown at 76. 70 As shown clearly in the drawings, the side and end plates are angle shaped and the horizontal legs 78 thereof extend inwardly to support the roof C. The side plates 74 are stiffened by plates 80 welded as at 82 to the respective legs of said 75 plates and extending diagonally across said legs.

As clearly shown in Fig. 8, the lifting ears 62 are connected to the side plates and to the side walls B by suitable fastening means such as the rivets 84 which also extend through the upper portions of the side walls. At the corners of the roof, 5 corner caps 85 are provided which rest against the legs of the post P and have top portions 87 which overlie the roof, and said caps are preferably welded to the posts and the roof sheets.

The roof C may of course be formed of a single 10 sheet if desired, but in the present instance is shown as formed out of a plurality of sheets 86 downwardly flanged as at 88 to lap the vertical legs of the side and end plates. The roof sheets are preferably connected to the side and end 15 plates and also to the upper edges of the side and end walls by welding such as shown at 90 in Figs. 8 and 17, the weld 90 effecting substantially a unitary construction including the side and end plates, the roof and the side and end walls. The 20 adjacent edges of adjacent roof sheets 86 are upwardly flanged as at 92 (see Figs. 9 and 10) and are arranged in contact with the vertical legs 94 of angle shaped carlines 96 and the flanges 92 are preferably welded to the carlines 96 as shown 25 at 98 thereby connecting adjacent roof sheets and the carlines. The ends of the carlines 96 extend into the side plates and the latter are preferably cut away as shown at 100 (see Fig. 9) to receive the vertical legs 94 of the carlines, the horizontal 30 legs of the carlines underlying the horizontal flanges 78 of the side plates and being welded thereto as shown at 102. The vertical legs 94 of the carlines are welded as at 104 to the side plates, As shown in Fig. 5 the side and end plates at 35 their adjacent edges are mitered as at 106 and are connected by gussets 108. For further supporting and stiffening the roof a ridge purlin 109 is provided (see Figs. 1 and 5) which is formed 40 in sections and is secured to the end plates, roof sheets and carlines.

As hereinbefore described the end walls overlap the end plates, and the front end wall D of the container is provided with a door opening which is normally closed by a door F, and said 45 front end wall includes a door header 110 and oppositely arranged vertical panels 112, the upper ends of which latter overlap and are preferably welded to an upper door frame member 126 hereinafter more fully described.

The panels 112 underlap the corner posts and are welded to the latter and to the corner post stiffener as shown at 114 (see Fig. 14) and extend to and overlap door posts 116 to which latter they are welded as shown at 118. The door posts 116 extend from the front end sill to the end plate and are connected to the latter by welding and are connected to the end sill by gussets 120 and said door posts comprise angles, legs 122 thereof extending inwardly as shown clearly in 60 Figs. 4 and 14 and the free edges of legs 122 are rearwardly bent as at 124 to define door post stiffeners.

The door opening is also framed by the before mentioned upper member 126 of angle form with 65 its vertical leg 128 welded to the header 110 adjacent its lower edge and projecting downwardly below the lower edge of header 110 to define a stop for the upper rail 130 of the door F, while the other leg 132 of the member 126 is inwardly 70 extended and then upwardly bent as at 134. The member 126 comprises a brace for the header 110 and extends in sections from corner post to corner post; the portion of said member between the door posts 116, in addition to its bracing ef- 75

fect defining the door frame member heretofore described.

The door F is hingedly connected as shown at 136 to the door post and the adjacent panel 112 5 and the panels 112 are each stiffened by means of internal horizontally arranged angles 138 welded to the door posts and the panels and having portions thereof lapping and welded to the post stiffeners; all as clearly shown in Fig. 14.

10 From the above description it is believed that those skilled in the art will recognize that a strong and durable container has been provided by the construction illustrated. The drawings include means whereby the container may be 15 lifted and moved about and these are usually essential in containers of great size. However it is obvious that the container of the present invention may be constructed of a size such that the lifting elements may not be required. The 20 present invention provides a container in which the body portion, base portion and roof are welded together to form substantially a unit. Riveting is eliminated thus eliminating inherent weaknesses in the usual type of riveted container.

25 The drawings herein illustrate one embodiment of the invention but it is to be understood that the drawings are illustrative only and various changes in the form and proportions of the construction shown may be made within the 30 scope of the appended claims without departing from the spirit of the invention.

What is claimed is:

1. In a container of the kind described comprising a base, side and end walls, side and end 35 plates of angle-shape secured to the walls at the upper portion thereof, the horizontal flanges of said plates extending inwardly, and being formed

with spaced marginal slots, internal braces for said side and end plates extending diagonally between the flanges thereof, carlines of angle-shape extending between said plates each having one flange positioned in the slots formed in the plate 5 and another flange extending through the adjacent internal brace and beneath the horizontal flange, and a roof supported by the side and end plates having marginal flanges lapping the vertical legs of said plates.

2. In a container of the kind described comprising a base frame including angle-shaped side and end sills having inwardly extending horizontal flanges, rigid floor beams extending between and supported by the side sills, horizontally arranged wood stringers supported by said floor beams, a floor supported by and secured to said beams and stringers, side and end walls, side and end plates of angle-shape secured to the walls at the upper portion thereof, the horizontal 20 flanges of said plates extending inwardly, and being formed with spaced marginal slots, internal braces for said side and end plates extending diagonally between the flanges thereof, carlines of angle-shape extending between said plates 25 each having one flange positioned in the slots formed in the plate and another flange extending through the adjacent internal brace and beneath the horizontal flange, reinforcing ribs for said side walls secured to said base, lifting ears, means for securing said lifting ears, side walls and plates together, and a roof supported by the side and end plates having marginal flanges lapping the vertical legs of said plates.
